UNITED STATES PATENT OFFICE

115,411

DESIGN FOR AN ELECTRICAL SELF-HEATING CUP

Herman E. Lacy, Chicago, Ill., assignor to
Helmeo, Inc., a corporation of Illinois

Application October 31, 1938, Serial No. 80,777

Term of patent 7 years

To all whom it may concern:

Be it known that I, Herman E. Lacy, a citizen of the United States, residing at Chicago, in the county of Cook and State of Illinois, have invented a new, original, and ornamental Design for an Electrical Self-Heating Cup, of which the following is a specification, reference being had to the accompanying drawing, forming part thereof.

Fig. 1 is a side elevational view of an electrical self-heating cup showing my new design.

Fig. 2 is a similar view but showing the parts in separated position.

I claim:

The ornamental design for an electrical self-heating cup, as shown and described.

HERMAN E. LACY.
